UNITED STATES PATENT OFFICE.

SETH A. CRONE, OF EAST ORANGE, NEW JERSEY.

RAILWAY BRAKE BEAM.

Application filed March 22, 1924. Serial No. 701,009.

To all whom it may concern:

Be it known that I, SETH A. CRONE, a citizen of the United States, and a resident of East Orange, in the county of Essex and 5 State of New Jersey, have invented certain new and useful Improvements in Railway Brake Beams, of which the following is a specification.

The invention pertains to railway brake beams and particularly to a four point suspension therefor and to guards extending lengthwise of the car truck and above the brake beams and cooperating with the respective tramway bars or members of the 10 four point suspension for holding the beams captive, while at the same time permitting the beams to have their requisite movements in the service application of the brakes to and their release from the car 15 wheels.

My invention comprises as one feature thereof special tramway bars to be engaged by the truss rod during the operation of the brake-beam, these bars being of channel 20 cross section and transversely curved on their upper surfaces and properly inclined and properly rigid to compel the proper application of the brakes to and their retirement from the wheels, as distinguished 25 from having a sagging uncertain action under the weight of the beams. The channel shape of the tramway bars permits me to provide rigid bars of great strength without undue weight of metal therein and the 30 transversely curved upper surface of these bars permits the end portions of the truss rod to ride upon the bars with limited resistance to and wear on the rod.

The guard bars which extend over the 35 brake beams are detachably connected at their outer ends to the outer ends of the tramway bars and these guard bars, in one embodiment of my invention, are of the same channel shape as the tramway bars 40 and hence of great strength without being unduly heavy. The brake-beams by being held captive or caged between the tramway bars and guard bars can neither fall to the road bed or be carried upwardly over 45 the wheels in the event of accident to the usual brake beam hangers.

The invention will be fully understood 50 from the detailed description hereinafter presented, reference being had to the accompanying drawings, in which:

Fig. 1 is a plan view, partly broken away,

of a car truck frame equipped with the four point suspension and safety features of my invention;

Fig. 2 is a vertical longitudinal section 60 through the same taken on the dotted lines 2-2 of Fig. 1;

Fig. 3 is a side view, on a larger scale, 65 of a portion of the outer end of one of the tramway bars;

Fig. 4 is an end projection of the same, taken from the right hand side of Fig. 3;

Fig. 5 is a plan view, on a larger scale, 70 of a portion of the outer end of one of the upper guard bars;

Fig. 6 is an end projection of the same, taken from the right hand side of Fig. 5;

Fig. 7 is a detached plan view, on a larger 75 scale, of a supporting plate secured to the spring plank of the truck for supporting the inner adjoining end portions of aligned tramway bars;

Fig. 8 is an end projection of the same, taken from the right hand edge of Fig. 7;

Fig. 9 is a front edge view of the same; 80

Fig. 10 is a vertical transverse section, 85 on a larger scale, through a portion of the spring plank and adjacent portions of the tramway bar and guard bar, taken on the dotted line 10-10 of Fig. 2;

Fig. 11 is a plan view, partly broken away, of a car truck frame equipped with a modified form of my invention;

Fig. 12 is a vertical longitudinal section 90 through the same taken on the dotted line 12-12 of Fig. 11, and

Fig. 13 is a vertical transverse section, 95 on a larger scale, through a portion of the spring plank, the tramway bar and the supporting plate for said bar, taken on the dotted line 13-13 of Fig. 12.

In the drawings, referring to Figs. 1 to 10 inclusive, 15 designates a portion of a well-known form of spring plank constituting a portion of a car-truck frame of usual 100 type, and 16, 17 indicate portions of inside-hung trussed brake-beams of customary type, each comprising the usual compression member 18, tension member 19 and strut 20. These brake beams are suspended by well known pivoted hangers, not shown, and carry the brake shoes, not shown, as usual.

My invention does not involve any change 110 in the brake-beams, their shoes or their hangers, which form two points of the suspension.

My invention pertains more especially to

the tramway bars 21, 22, which are duplicated at opposite sides of the truck, as usual, and form two means of suspension for the brake-beams, to the bar 23 secured to the 5 spring plank and at its ends affording the guard members 24, 25 extending over the brake beams and detachably receiving at their outer ends the outer ends of said tramway bars, said bar 23 being duplicated at 10 opposite sides of the truck, and to the means for supporting the inner end portions of the tramway bars from the spring plank, said means comprising a plate 26 riveted to the lower side of the spring plank and having a 15 longitudinal channel 27 to receive the inner end portions of two aligned tramway bars 21, 22 and upwardly deflected spring sections 28, 29 for pressing the inner end portions of said bars upwardly against the 20 lower surface of the spring plank.

The aligned tramway bars 21, 22 are alike in every detail and said bars extend longitudinally, one forwardly and the other rearwardly, below the brake-beams 16, 17. Each 25 tramway bar has a plain straight horizontal base section 30 and an upwardly and outwardly inclined section 31 which serves as a support and guide for the end portion of the truss rod 19. The tramway bars are distinctive in that they are throughout of channel shape and have downwardly extended edge flanges and an upwardly convexed web, as shown in Figs. 4 and 10, whereby 30 said bars are rendered strong and rigid and 35 present rounded or transversely curved upper surfaces to the truss rods, this being important since thereby no sharp corners of the bars are permitted to be in contact with the truss rods at any time.

40 The inclined sections 31 of the tramway bars are of the proper inclination to guide the truss rods in such manner that the brake shoes are correctly applied to and retired from the wheels, and the rigidity of the 45 tramway bars is such as to avoid uncertain sagging thereof under the weight of the brake beams. The upper outer ends of the inclined sections 31 of the tramway bars have their edge flanges cut away and the 50 web of the bars at said ends bent into the form of a sleeve or hinge-knuckle 33 (Fig. 3) for a purpose to be hereinafter described. The base sections 30 of the tramway bars are straight out to a point below the 55 compression members 18 of the brake beams, and preferably the tramway bars 21, 22 are in two separate pieces each being complete in itself for its brake beam, and these two bars are slidable at their inner aligned end 60 portions into the channel 27 of the supporting plate 26, which plate is secured to the spring plank 15 by means of rivets 34. The inner ends of the base members of the bars 21, 22 are inserted endwise into the respective ends of the channel 27 and pass into

abutting relation with each other centrally below the spring plank 15, and said bars are removable from the channel 27 when necessary, not being riveted to said spring plank. When the inner ends of the bars 21, 22 are 70 inserted through the respective ends of the channel 27, said bars flex the spring sections 28, 29 downwardly, and thereafter said spring sections act with a strong spring pressure upwardly against the inner ends of 75 said bars and serve to bind them firmly against the lower surface of the spring plank 15, said spring sections 28, 29 serving to steady the bars 21, 22 at their inner end portions and make up for any irregularities 80 there might possibly be in the facing surfaces of the bars with the spring plank and plate 26. The edge flanges on the bars 21, 22 snugly fit within the angular walls of the channel 27 and against the base of said channel, as shown in Fig. 10.

The four point suspension structure hereinbefore described is complete in itself for operative use, especially if I secure the inner ends of the tramway bars to the spring plank in the manner shown in Fig. 12, but I prefer to apply certain safety features to cooperate with the tramway bars 21, 22 so that the brake beams may be held captive and neither fall to the roadbed nor be carried upwardly by the wheels, should the brake hangers become damaged, and to this end I make use of the safety bar 23 whose middle portion is bent downwardly to fit between the flanges 35 of the spring plank 15 and against the upper surface of said plank, as shown in Fig. 2, said portion of the bar 23 being secured down against the spring plank by means of straps 36 which loop over the bar 23 at its middle portion and are secured at their ends to the spring plank by the same rivets 34 which secure the supporting plate 26 to the lower surface of the spring plank. The opposite inner portions of the bar 23 slant upwardly and outwardly from the spring plank 15 and thence project outwardly in opposite longitudinal directions to form the guards 24, 25, which extend above the beams 16, 17 and at their outer ends are detachably connected with the tramway bars 21, 22, respectively, by pins 37 which extend through apertured wings 38 formed on the ends of the bar 23 and through the sleeve or knuckle 33 formed on the outer ends of the tramway bars, as shown in Figs. 1 and 2. The wings 38 are formed by splitting the ends of the bar 23 longitudinally for a short distance through the web thereof and then twisting the opposite edge portions of the ends of the bar into vertical position and curving the same downwardly, as shown in Fig. 2, to suitably receive between them the sleeve 33 of the tramway bars and operate as hinge-knuckles or as convenient 110 115 120 125 130

means for detachably connecting the tramway bars and guard bars together. The sand plank 15 shown is shallow and is a common form of sand plank, but some 5 spring or sand planks in car trucks have a deeper channel than the sand plank 15 illustrated, and it will appear obvious that the portions of the bar 23 which extend upwardly from the sand plank must 10 form to the flanges that may be on the sand plank so as to extend upwardly along the facing sides thereof and then project outwardly over the edges of said flanges. The bar 23 is preferably in one integral piece from 15 end to end, and said bar is also preferably of channel shape in cross-section, as shown in Fig. 10, so that the bar may possess strength and rigidity without undue weight of metal, it not being intended that said 20 bar shall have any appreciable yielding action under the weight of the brake beams. I preferably form the bar 23 and tramway bars 21, 22 of the same stock, as represented in Fig. 10, and so dispose the bar 23 that its 25 upwardly convexed web is exposed at the upper side of said bar, thus leaving smooth surfaces both for the sake of appearance and for convenience in handling and forming the bar.

30 The supporting plate 26 is flanged downwardly at its front and rear edges, as at 39, for the purpose of strengthening the edges of the plate 26 at the points at which the tramway bars 21, 22 would exert the 35 greatest pressure against said plate.

In assembling the several features of the invention, I first secure the bar 23 on the upper side of the spring plank 15 and secure the supporting plate 26 on the lower side of 40 said plank by applying the straps 36 over the bar 23 and securing said straps and the plate 26 by means of the rivets 34. After this has been done the adjoining ends of the tramway bars 21, 22 may be forced into the 45 opposite ends of the channel 27 of the plate 26 and toward each other until they abut centrally below the spring plank, the spring sections 28, 29 being flexed downwardly by the insertion of said bars 21, 22 into the 50 channel 27. Thereafter the pins 37 will be applied for the purpose of detachably connecting the outer ends of the tramway bars with the outer ends of the guards 24, 25. Whenever it may be necessary to remove the 55 tramway bars 21, 22 the pins 37 may be withdrawn and said bars pulled outwardly from the channel 27 of the supporting plate 26. I therefore preferably form the guards 24, 25 from one integral bar 23 and have the 60 tramway bars 21, 22 in two separate pieces supported at their inner ends by the plate 26 and detachably connected at their outer ends by any suitable means with the outer ends of the guards 24, 25. The rigidity of 65 the bar 23 and bars 21, 22 makes it un-

necessary to rivet the inner ends of the tramway bars to the spring plank, since said bars cannot slide outwardly from the supporting plate 26 until after the pins 37 have been withdrawn for disconnecting said bars from 70 the guards 24, 25.

I desire to call attention to the fact that in the construction hereinbefore described the inner ends of the tramway bars when inserted into the channel of the plate 26 75 come up against abutments, these abutments, in the illustration of my invention presented herein, being, for each bar, the inner end of the other bar, and that said tramway bars are secured in position 80 without the use of bolts or rivets extending through them and the spring plank; the tramway bars are therefore removable from the spring plank without cutting any rivets or removing any bolts 85 from the spring plank. When tramway suspension bars are secured to the spring plank by bolts or rivets extending through them and the spring plank, the pressure of 90 the brake beams against said bars and the conditions of car truck service generally, cause said bars to be driven against said bolts or rivets with a shearing action, and this is one of the objections my invention remedies in that the bars are not bolted or 95 riveted to the spring plank but are supported at their inner end portions within the channel of the independently and permanently secured plate 26 and are resisted against inward thrust by abutments within the plate 26 instead of by rivets or bolts entering the bars and the spring plank. I have found that it is sufficient that the inner ends of the bars 21, 22 abut against 100 each other within the plate 26 but I do not confine my invention to this method of providing abutments for the inner ends of said bars, the only essential consideration being that the bars have points of resistance within the plate 26 without the use of rivets or bolts extending through the bars.

In Figs. 11, 12 and 13 I illustrate a modification of a portion of the invention, this modification residing mainly in the omission of the guards 24, 25 of Fig. 2 and in detachably securing the tramway bars to the spring plank by means of pins 40 and cotter keys 41. In Figs. 11, 12 and 13, 42 denotes the spring plank, 43, 44 designate the brake beams, 45, 46 the tramway bars and 47 indicates a channel supporting plate secured to the spring plank 42 by means of rivets 48 and receiving the inner end portions of the tramway bars, which as aforesaid, are detachably secured in place by means of the pins 40 and keys 41. The spring plank, 115 brake beams and tramway bars shown in Figs. 11, 12 and 13 are the same as the like features illustrated in Figs. 1 to 10 inclusive 120 and therefore require no special description.

125 130

- The omission of the guards 24, 25 from the construction shown in Figs. 11, 12 and 13 makes it unnecessary to form the sleeves 33 on the upper ends of the tramway bars 5 45, 46 and otherwise the bars 45, 46 are of the same construction as the bars 21, 22 of Fig. 2. The absence of the guards 24, 25 from the construction shown in Fig. 12 renders it necessary that the guard bars be fastened 10 to the spring plank and to effect this result I make use of the detachable pins 40 and keys 41. Figs. 11, 12 and 13 are presented to indicate that that portion of the invention relating to the tramway bars is not 15 necessarily limited to the employment of the guard bars 24, 25, but I deem it very desirable that said guard bars be made use of, because of the benefits to be derived from their use.
- 20 Spring planks or sand planks of car trucks vary in design and details and hence I use the term spring plank herein in a generic sense as applying to spring planks generally.
- 25 What I claim as my invention and desire to secure by Letters-Patent, is:
1. A car-truck having a trussed brake-beam, a tramway suspension bar therefor, means secured to the spring plank for removably receiving the inner end of said tramway bar, and a guard bar rigidly secured to a truck member and extending outwardly over said suspension bar and above the brake-beam and detachably connected with the outer end of said tramway bar, said tramway bar 30 35 when freed from the guard bar being detachable, and said guard bar being removable.
  2. A car-truck having a trussed brake-beam, a tramway suspension bar therefor, and a guard bar rigidly secured to a truck member and extending outwardly over said suspension bar and above the brake-beam and detachably connected with the outer end of said tramway bar, said tramway bar 40 45 when freed from the guard bar being detachable, and said guard bar being of channel form.
  3. A car-truck having a trussed brake-beam, a tramway suspension bar therefor, and a guard bar rigidly secured to a truck member and extending outwardly over said suspension bar and above the brake-beam and detachably connected with the outer end of said tramway bar, said tramway bar 50 55 when freed from the guard bar being detachable, and said guard bar being of inverted channel form having an upwardly convexed web.
  4. A car-truck having a trussed brake-beam, a tramway suspension bar therefor, and a guard bar rigidly secured to a truck member and extending outwardly over said suspension bar and above the brake-beam and detachably connected with the outer end 60 65 of said tramway bar, said tramway bar and

said guard bar being of corresponding channel form.

5. A car-truck having a trussed brake-beam, a tramway suspension bar therefor, and a guard bar rigidly secured to a truck member and extending outwardly over said suspension bar and above the brake-beam and detachably connected with the outer end of said tramway bar, said tramway bar and said guard bar being of corresponding channel form having depending side edge flanges and upwardly convexed webs. 75

6. A car-truck having a trussed brake-beam, a tramway suspension bar therefor, and a guard bar rigidly secured to a truck member and extending outwardly over said suspension bar and above the brake-beam and detachably connected with the outer end of said tramway bar, the outer end of said tramway bar and the corresponding end of the guard bar having cooperating apertured parts to detachably receive a connecting pin. 80

7. A car-truck having inside hung trussed brake-beams, aligned tramway suspension bars therefor and a longitudinal bar secured at its middle portion to the spring plank and thence at its end portions extending outwardly over the tramway bars and above the brake-beams to form safety guard bars and being connected at its outer ends to the outer ends of said tramway bars. 90 95

8. A car-truck having inside hung trussed brake-beams, aligned tramway suspension bars therefor and a longitudinal bar secured at its middle portion to the spring plank and thence at its end portions extending outwardly over the tramway bars and above the brake-beams to form safety guard bars and being connected at its outer ends to the outer ends of said tramway bars and said longitudinal bar being of channel form. 100 105

9. A car-truck having inside hung trussed brake-beams, aligned tramway suspension bars therefor and a longitudinal bar secured at its middle portion to the spring plank and thence at its end portions extending outwardly over the tramway bars and above the brake-beams to form safety guard bars and being connected at its outer ends to the outer ends of said tramway bars, said tramway bars and said longitudinal bar being of inverted channel form. 110 115

10. A car-truck having inside hung trussed brake-beams, aligned tramway suspension bars therefor and a longitudinal bar secured at its middle portion to the spring plank and thence at its end portions extending outwardly over the tramway bars and above the brake-beams to form safety guard bars, said tramway bars at their outer ends being detachably connected with the outer ends of said longitudinal bar and at their inner end portions being supported from the spring plank and detachable there- 120 125 130

from when the tramway bars are freed from said longitudinal bar.

11. In a car-truck having a spring plank and a trussed brake-beam, a tramway suspension bar for said beam, a guard bar secured to a truck member and extending outwardly over said suspension bar and above the brake beam and connected at its outer end with the outer end of the suspension bar, and a plate below the spring plank and secured thereto having a channel into which the inner end portion of the suspension bar may be introduced endwise and which plate is adapted to securely support said bar at its inner end portion while the outer end portion thereof is sustained by said guard bar.

12. In a car-truck having a spring plank and trussed brake-beam, a tramway suspension bar for said beam, a guard bar secured to a truck member and extending outwardly over said suspension bar and above the brake beam and connected at its outer end with the outer end of the suspension bar, and a plate below the spring plank and secured thereto having a channel into which the inner end portion of the suspension bar may be introduced endwise and which plate is adapted to securely support said bar at its inner end portion while the outer end portion thereof is sustained by said guard bar, said guard bar resisting outward movement of said tramway bar from said plate and an abutment being provided to resist undue inward movement thereof.

13. In a car-truck having a spring plank and inside hung trussed brake-beams, aligned tramway suspension bars for said beams, guard bars secured to a truck member and extending outwardly over said suspension bars and above the brake-beams and connected at their outer ends with the outer ends of said suspension bars and a plate below the spring plank and secured thereto having a channel into which the inner end portions of said tramway bars may be introduced endwise and which plate is adapted to support said tramway bars at their inner end portions while the outer portions thereof are sustained by the respective guard bars.

14. In a car-truck having a spring plank and inside hung trussed brake-beams, aligned tramway suspension bars for said beams, guard bars secured to a truck member and extending outwardly over said suspension bars and above the brake-beams and connected at their outer ends with the outer ends of said suspension bars and a plate below the spring plank and secured thereto having a channel into which the inner end portions of said tramway bars may be introduced endwise and which plate is adapted to support said tramway bars at their inner end portions while the outer portions thereof are sustained by the respective guard bars, of are sustained by the respective guard bars, said guard bars resisting outward movement of said tramway bars from said plate and abutments being arranged to resist undue inward movement thereof.

15. In a car-truck having a spring plank and inside hung trussed brake-beams, aligned tramway suspension bars for said beams, guard bars secured to a truck member and extending outwardly over said suspension bars and above the brake-beams and connected at their outer ends with the outer ends of said suspension bars and a plate below the spring plank and secured thereto having a channel into which the inner end portions of said tramway bars may be introduced endwise and which plate is adapted to support said tramway bars at their inner end portions while the outer portions thereof are sustained by the respective guard bars, the channel in said plate permitting said tramway bars to pass into abutting relation with each other at their inner ends.

16. In a car-truck having a spring plank and inside hung trussed brake-beams, aligned tramway suspension bars for said beams, guard bars secured to a truck member and extending outwardly over said suspension bars and above the brake-beams and connected at their outer ends with the outer ends of said suspension bars and a plate below the spring plank and secured thereto having a channel into which the inner end portions of said tramway bars may be introduced endwise and which plate is adapted to support said tramway bars at their inner end portions while the outer portions thereof are sustained by the respective guard bars, said tramway bars being detachable from said guard bars and when detached therefrom being adapted to be withdrawn from the channel of said plate.

17. In a car-truck having a spring plank and a trussed brake-beam, a tramway suspension bar for said beam, a guard bar secured to a truck member and extending outwardly over said suspension bar and above the brake beam and connected at its outer end with the outer end of the suspension bar, and a plate below the spring plank and secured thereto having a channel into which the inner end portion of the suspension bar may be introduced endwise and which plate is adapted to securely support said bar at its inner end portion while the outer end portion thereof is sustained by said guard bar, said tramway bar being detachable from said guard bar and when detached therefrom being adapted to be withdrawn from the channel of said plate.

Signed at New York city, in the county of New York and State of New York, this 21st day of March, A. D. 1924.

SETH A. CRONE.
